UNITED STATES PATENT OFFICE.

DARIO ROBERTI, OF SPRINGFIELD, MASSACHUSETTS.

LOCK.

Application filed April 5, 1923. Serial No. 630,162.

This invention refers to locks and more particularly to combination locks for use with doors for buildings. Some of its objects include the provision of the following features:

To have a lock adaptable for the purpose in question and yet not take up any more room than an ordinary lock.

To have the lock adaptable for a large number of combinations.

To have it adaptable as an ordinary lock.

To have the lock in sections, each of which can be made, and inspected or repaired independently of the other.

To have it provided with features to prevent tampering by unauthorized persons.

And many other objects which will become apparent as the invention is more fully set forth.

Combination or permutation locks are not ordinarily adapted for use with ordinary building doors because of their elaborate and cumbersome construction, and the difficulty of arranging their parts to come where they could be actuated from the front or back of a door. This invention not only provides for all the features that are met with in doors for locks, but in addition can be used as an ordinary lock readily, to be reset as a combination lock at a moment's notice. The lock is keyless and has the appearance of an ordinary lock, with handle and latch.

The lock is provided with its locking mechanism in one unit, and its operating mechanism in another so that each may be separated from the other.

In the drawings:

Figure 1 is a front elevation of a lock embodying this invention as seen from the front of the door in which it is located.

Figure 2 is a side elevation of Figure 1.

Figure 3 is a rear elevation of the lock.

Figure 4 is a view through the lock looking behind the front plate.

Figure 5 is a view looking through the rear face plate of the lock.

Figure 6 is an enlarged detail in perspective of parts indicated in Figure 5.

Figure 7 is a side elevation indicating the push-button mechanism of the lock.

Figure 8 is a detail of the latch parts of the locking perspective.

Figure 9 is a detail in perspective and diagram of the lock and parts partially separated and with alarm attachment.

Figure 10 is a diagrammatic view of the lock operation in its various steps.

Figure 11 is a detail of the bolt for locking the false section to the interior section of the lock.

Figure 12 is a detail of the rack and set keys of the lock.

Figure 13 is a detail of the lock bar and operating link.

Similar reference character refer to similar parts throughout the drawings.

The lock construction embodying this invention is shown mounted in a door 1, having the usual slots and holes for the lock parts that require them.

The lock consists of five main elements, namely: a front plate 2, secured to the front of the door 1 with screws 3; a rear plate 8 on the back of the door secured with screws 3; an inner casing 12 within the lock slot of the door; a false section 19 insertable in the inner casing; the operating parts and devices consisting of push-buttons and the like; and handle parts for operating the latch mechanism of the lock.

The front plate 2 is provided with a door knob 7 and the bar for the same passes through to the other side of the door to another similar knob 7 in the usual manner. Several push buttons 4 resiliently project from the plate 2 and are provided for functioning as the motive part for actuating the operative mechanism of the lock. A special resilient push key 5 is also mounted on this plate and serves to release the permutation parts of the lock. It is preferably provided with some means for locking it pushed-in when necessary.

A push button 6 is also provided on this plate, and is used for snapping the catch of the lock in a manner to be described.

The rear plate 8 has a push button 16 used for the same purpose as button 6. This plate also has a resilient push key 15 rotatable clockwise and counterclockwise and adapted to operate the locking bar 29 in a sidewise parallel movement through a link, slot and pin, 37, 38 and 39 as shown in Fig. 13.

A night snap 10 is mounted on the plate and serves to lock the permutation mechanism of the lock. A release 11 relieves the snap when desired, so as to make it disconnect from the permutation mechanism. The various push buttons and keys project through their respective plates and the door

into the casings and section so as to coact with the mechanism intended to be operated by them.

The inner casing 12 has the main latch mechanism of the lock. It has a latch 14 with its permutation slots 45, coiled spring 46 and slots 47 with guide pins to control the travel of the latch. A trip 48 serves as means for enabling the cam 17 of the handle bar to pull the latch back against the tension of the spring 46, so as to unlock the door, when the knob is turned.

An auxiliary resilient catch 49 catches in a slot 50 in the latch and serves to limit the movement of the latch, until the operation of the push buttons 6 or 16 press on its levers 51 to take it out of the slot. The latch slides on a plate 52.

Each push button 4 operates a resilient pawl 25 that engages with its respective rack teeth and lifts the rack 26 in the false section 19. A resilient restraining member 24 is mounted over each pawl and serves to hold the respective racks properly positioned after being acted upon by the pawls and push buttons. A bar 31 rests against the front of the restraining members as indicated and is held by arms 54 pivoted at the sides 55 and connected at the bottom by a bar 56 crossing underneath as shown. The last bar is pressed upon by the push key 5 which is in the rear of the bar in the plate 2. This casing is arranged with channels 18 adapted to receive the edge portions of the false section 19. The casing has a face plate 13 which is provided with a slot for the latch 14 and with projections 57 to catch on the bolt 21, when the false section is locked in the casing.

The upper portion of the casing is provided with a plate and electrical connections for causing an alarm if the combination of the lock is operated wrongly, the connections being arranged for in any conventional manner.

The false section 19 has a series of T bars 27 numbered 1, 2, 3, 4, 5, 6 for identification and connected vertically to the back of the section with channels 68 formed between them to take the set keys 28 and the rack bases, so that they slide readily in them as described. The set keys have each a lip arranged to rest on the locking or supporting bar 29, when they are not raised by the operation of the racks. The set keys have a part 59 adapted to engage in the slots 45 of the latch to hold it from moving, while so placed.

The locking bar 29 is provided with slots 34 and guide pins to control its movement in a slanting direction as shown. It has a catch 60 on its end portion that engages under the bolt 33 and locks the same when the lock is set, as shown in Fig. 6.

A stop bar 35 limits the downward move-

ment or position of the racks. A leaved spring member 30 projects beyond the false section and is stressed under pressure when the section is placed in the casing so as to tend to come out of the casing when the bolts holding the same in place are released.

The false section has a face plate 23 arranged to close the door edge side of the lock. A tongue 22 is recessed in the face of the plate 23 and pivots therein with an arm 61 against the bolt 21, which it moves into an unlocking position when the tongue is raised as shown in Figure 5. The bolt is mounted on the face plate 23 and has lips 20 that engage on the projections on the face plate of the casing.

The operation of the device involves for three main functions namely, locking, unlocking and removal, as well as several minor functions.

The process of locking requires the setting of the set keys in the slots of the latch so that the latter cannot move, and placing the locking bar when the bolt 21 cannot be operated and the false section taken out. To produce this, the push button 6 or 16 is operated to release the auxiliary catch and cause the latch to travel its full length, or in other words snap the catch. The key 5 is then pushed, which allows the racks and set keys to fall into place and lock the latch. Bar 29 is down so that the false section cannot be taken out.

The unlocking process, consists in raising the bar 29 by turning key 15 clockwise; pushing the push key 5 in so as to get the restraining members out of the way; and then lift tongue 22 so that the bolt 21 unlocks the false section from the casing. The spring member 30 will then help to push the false section out. When the false section is out the set keys and racks can be changed or interchanged as much as desired to change the combination of the lock. They lift right out and are interchangeable.

To work the combination in unlocking, the push buttons 4 are pushed, and made to raise the respective racks until they disengage the set keys out of the slots in the latch. When this is done the handle or knob 7 is turned, the cam acting on the latch.

The other parts have been described and their functions indicated, which in connection with the drawings can be readily understood. The device is subject to many arrangements and conditions. It is of course understood that the false casing cannot be removed until the knob and handle bar is taken out, which is a comparatively simple manner.

Claims:

1. A lock of the class described comprising in combination, a casing having a latch mechanism therein and a face plate there-

- for, permutation means, a false section insertable in the casing having a plurality of devices for catching in the latch mechanism so as to lock the same in a predetermined manner, said devices being actuated by said permutation means, means for latching said section in said casing, a plurality of buttons for actuating the permutation means according to a predetermined arrangement, and 10 push buttons for setting or resetting the permutation means, auxiliary means for detaching the permutation means from the buttons whereby it will become inoperable by said buttons, a supporting bar for the 15 permutation means, and means for dogging the said section latching means for preventing the false section from being removed from the casing, and handle means for turning the latch.
- 20 2. A lock of the class described comprising in combination, a casing having a latch mechanism therein and a face plate therefor, permutation means comprising slidable racks in guides and pivoted pawls for controlling 25 the movement of the racks, a false section insertable in the casing having a plurality of set keys for catching in the latch mechanism so as to lock the same in a predetermined manner, said set keys being actuated by said permutation means, means for latching said section in said casing, a plurality of push buttons for actuating the permutation means according to a predetermined arrangement and buttons for setting or resetting the permutation means, auxiliary 30 means for detaching the permutation means from the buttons whereby it will become inoperable by said buttons last mentioned, a supporting bar for the permutation means and means for dogging the false section 35 latching means for preventing the false section from being removed from the casing, means for unlocking the said dogging means at predetermined arrangements of the permutation means and parts connected therewith, and a handle mechanism for turning the latch.

In testimony whereof I hereunto affix my signature.

DARIO ROBERTI.
